UNITED STATES PATENT OFFICE

DWIGHT M. ANDERSON AND ARTHUR W. MCNEISH, OF EAST CLEVELAND, OHIO

FASTENING FOR HUB CAPS, RADIATOR CAPS, AND GASOLINE TANK CAPS

Application filed September 21, 1929. Serial No. 394,336.

Our invention relates to fastenings for hub caps, radiator caps and gasoline tank caps, or the like.

One object is to provide an interchangeable cap that can be used on standard cars in any one of the three positions above mentioned.

Another object is to provide a quick, sure method of locking the cap in the correct position.

Other objects will appear from the following description in conjunction with the drawings which form a part of this specification.

15 Referring to the drawings:

Fig. 1 shows the invention in use as a hub cap.

Fig. 2 is a broken partial section on line 2-2 of Fig. 1.

20 Fig. 3 is an enlarged rear view of the hub cap.

Fig. 4 is a section taken on line 4-4 of Fig. 3.

25 Fig. 5 is a broken section of the body of the cap with a section of the locking spring.

Fig. 6 shows a section of the body of the neck to which the cap is fitted, taken on line 6-6 of Fig. 7.

Fig. 7 is a plan view of the neck.

30 Fig. 8 is a sectional view of the invention when used as a cap for gas tanks.

Fig. 9 is a section in plan taken approximately on line 9-9 of Fig. 8 with springs exposed.

35 Fig. 10 is a sectional view of the invention when used as a cap for the radiator.

Fig. 11 is a perspective view of the locking spring.

Fig. 12 is a side elevation of the spring, 40 showing the slightly raised portion on the end of the spring.

In the drawings 1-1' and 1A represents the body or outer shell of the cap which may be formed with a curved or flat surface as desired, both of which are indicated at 45 2 and 2A, within the cap body is an inner plate, or shell 3 which in Fig. 4 is formed with a depression 4, and portions 3' and 3A are cut at intervals at 5 for the locking 50 springs 6, which protrude through slots in

cap boss 8 and lock in the cut out portions or notches 5, the raised portions 13 riding over the raised ribs 7 of the cap boss 8, which locks the cap in position. The springs 6 are pivoted on pins 9 journaled in cap boss 8 and are held in place by washer 10 and bolt 11 or 11A, and a gasket 12 is inserted between the outer shells 1' and 1A and body portions 3' and 3A to ensure an air tight cap when in locked position.

With a twisting movement of the outer shell 1-1' and 1A the springs 6 open or close to release or lock the cap in position. That is, when the cap is placed on the neck to which it is to be applied the ends of the springs 6 will pass through the recesses 5. Then by turning the cap the springs are extended or projected outwardly under the flange of the cap, and riding along the ribs 7 will be pressed by said ribs to close contact with the under or inner side of the flange adjacent the recesses 5, thereby clamping the cap to the neck and pressing the gasket 12 against the shoulder of the neck. Thus by spring pressure the cap is held tightly against the neck and loss thereof is prevented. The same cap may be used in any one of the various locations indicated, by providing a neck opening and conformation similar to that described.

While the construction and arrangement of parts have been described more or less specifically, it is to be understood that obvious modifications may be made as come within the scope of the appended claims.

85 We claim:

1. The combination with a neck having a recessed flange, of a cap fitting upon the neck and having flat springs pivoted thereto and adapted to be entered through the recesses and slidable outwardly to engagement behind the flange by turning the cap.

2. The combination stated in claim 1, the cap having ribs along which the springs ride as they slide when the cap is turned, to press the springs in tight contact with the flange.

3. The combination with a neck having a flange projecting inwardly, with notches at its inner edge, of a cap fitting upon the

neck and provided with tangential springs pivoted at their inner ends to the cap, and engageable behind the flange of the neck by entering the outer ends of the springs through said notches and turning the cap to project the springs outwardly behind the flange.

4. The combination stated in claim 3, the cap having ribs behind the springs upon which the springs ride when the cap is turned, to clamp the springs against the flange.

In testimony whereof, we do affix our signatures.

15 DWIGHT M. ANDERSON.
ARTHUR W. McNEISH.
